273, 274; 324/156, 158 F[57] **CLAIM**

The ornamental design of an electronic measurement instrument, as shown and described.

DESCRIPTION

FIG. 1 is a front elevation view of an electronic measurement instrument showing our new design;

FIG. 2 is a bottom side elevation view thereof;

FIG. 3 is a back side elevation view thereof;

FIG. 4 is a top side elevation view thereof;

FIG. 5 is a left side elevation view thereof; and,

FIG. 6 is a right side elevation view thereof.

The broken line showings are for illustrative purposes only and forms no part of the claimed design.

UNITED STATES PATENT AND TRADEMARK OFFICE
CERTIFICATE OF CORRECTION

Page 1 of 5

PATENT NO. : Des. 366,432

DATED : January 23, 1996

INVENTOR(S) : Jerry L. Wrisley et al

It is certified that error appears in the above-identified patent and that said Letters Patent is hereby corrected as shown below:

The title page, showing an illustrative figure, should be deleted and substitute therefor the attached title page.

In the drawings, delete Sheets 1-3, consisting of FIGS. 1-6, and substitute therefor Sheets 1-3, as shown on the attached pages.

Signed and Sealed this
Third Day of June, 1997

Attest:

BRUCE LEHMAN

Attesting Officer

Commissioner of Patents and Trademarks
